UNITED STATES PATENT OFFICE.

JOHN H. CRUTCHFIELD, OF SPARTA, ILLINOIS.

ELEVATOR SAFETY APPLIANCE.

Application filed April 7, 1922. Serial No. 550,446.

To all whom it may concern:

Be it known that JOHN H. CRUTCHFIELD, a citizen of the United States of America, residing at Sparta, in the county of Randolph and State of Illinois, has invented new and useful Improvements in Elevator Safety Appliances, of which the following is a specification.

The object of the invention is to provide a simple and efficient means for catching and holding an elevator cage in the event of the breakage of the hoisting cable or the disarrangement of the operating means so as to leave the cage in an otherwise unsupported condition; and with this object in view the invention consists in a construction and combination of parts of which a preferred embodiment is shown in the accompanying drawings, wherein:—

20 Figure 1 is an elevation of an elevator cage and shaft equipped with a safety appliance constructed in accordance with the invention.

Figure 2 is a transverse sectional view of 25 the same taken on the plane indicated by the line 2—2 of Figure 1.

Figure 3 is a detail view in plan of the attaching links by which connection is made between the hoisting cable and the cage.

30 The cage which is indicated only in outline at 10 and obviously may be of any preferred construction adapted either for passenger use or for hoisting minerals such as coal, ore and the like as for example from mines or similar sources of supply and frequently employed particularly in mine shafts as a convenient means of hoisting the workmen to the surface, and parallel with the guiding tracks 11 of the shaft or frame in 35 which the elevator cage is mounted to slide are arranged racks 12 for traverse by gears 13 revolvably mounted as at 14 upon the car in a common transverse plane and also in the common plane of the racks, and designed to rotate in opposite directions as 40 the car is elevated and lowered.

The adjacent portions of the peripheries of the gears approach to within a comparatively short distance of each other and arranged above the same for movement in a plane common therewith is a wedge shaped locking block 15 having toothed downwardly convergent faces 16 which are adapted when the block is lowered to interlock with the 45 teeth of the gears and thereby hold the latter against rotation in a direction to permit

downward movement of the cage. This locking block is adapted to find a position in interlocking engagement with the gears by gravity when suspended in the construction illustrated when in a position above the plane of approach of the peripheries of the gears, but as an auxiliary means of actuating the locking block and as a means of holding the same against vibration in the 50 operation of the cage, and furthermore as a means of insuring the operative engagement of the block with the gears should the direction of movement necessary to interlock the same be other than downward, as 55 might occur in certain conceivable arrangements of elevator mechanisms, there is employed a block actuating spring 16 connected to the apex or reduced end of the block and to a suitable portion of the car frame such 60 as the bar 17, the tension of the spring being continuously directed to a movement of the block into its engaging relation with the 65 gears.

In the construction illustrated the car is 70 supported for elevation and lowering movements by a hoisting cable 18 connected with the car by means of the supporting links 19 with which the cable has a lost motion connection through an elongated guide link 20, and connecting the locking block with this hoisting element is a retainer 21 consisting 75 as shown of a light chain or its equivalent which is sufficient when the hoisting cable is under tension due to the weight of the car to hold the locking block in the inoperative 80 position indicated in Figure 1 in opposition to gravity and the seating spring 16 or other yielding means tending to advance the block 85 into operative engagement with the gears.

Under ordinary working conditions the locking block, therefore, is held out of engagement with the gears and the operation of the elevator corresponds with those now in common use in mine shafts and the like, but in the event that the hoisting cable should break or the drum actuating clutch or brake of the engine should fail to operate or respond to the control of the operator and thereby permit the cable to pay out at an excessively rapid rate, the locking block will immediately be moved into interlocking engagement with the gears and obviously when in engagement the action of the gears thereon will tend to force the block downwardly into a position between the gears and thus force the gears outward to exert a 90 95 100 105 110

spreading action upon the racks and thus bind the car and lock it in a fixed position.

Moreover it will be obvious that the action of the block will occur immediately upon the release or reduction of strain on the cable and that immediately the braking action incident to its engagement with the gears will occur so that not more than a few inches of drop of the car can occur in the event of an accident before the locking thereof ensues, and hence before any considerable momentum can be acquired by the car.

Having described the invention, what is claimed as new and useful is:—

A safety appliance for elevators comprising vertically disposed racks arranged parallel with each other, an elevator car mounted for movement between the racks, gear wheels journaled upon the car and meshing with the teeth of the respective racks, said gear wheels lying in the same plane and being spaced from each other at their inner sides,

a locking block lying in the plane of the gear wheels and provided at its side edges with teeth, a spring connected at one end with the car and connected at its opposite end with the locking block, links connected with the upper portion of the car, means flexibly connecting the inner ends of the links with the locking block, a hoisting cable flexibly connected with the inner ends of the links, the parts being so arranged that when the car is being lifted by the pull of the cable, the inner ends of the links are elevated and the locking block is held spaced from the peripheries of the gear wheels, and when the cable becomes slack, the locking block is drawn into engagement with the perforations of the gear wheels by the action of the spring which is connected with the block and the car.

In testimony whereof he affixes his signature.

JOHN H. CRUTCHFIELD.
